UNITED STATES PATENT OFFICE.

THEODORE SCHEFFLER, OF PATERSON, NEW JERSEY, ASSIGNOR, BY DIRECT AND MESNE ASSIGNMENTS, TO OTTO FLOHR, OF NEWARK, N. J., AND FRANCIS M. PIERCE, OF BROOKLYN, N. Y.

FRICITION-CLUTCH.

SPECIFICATION forming part of Letters Patent No. 292,140, dated January 15, 1884.

Application filed October 31, 1883. (No model.)

To all whom it may concern:

Be it known that I, THEODORE SCHEFFLER, a citizen of the United States, residing at Paterson, in the county of Passaic and State of New Jersey, have invented certain new and useful Improvements in Friction-Clutches, of which the following is a specification.

This invention relates to that class of friction-clutches which couples one rotary part to another when revolving in one direction, but automatically uncouples them when a reverse rotation is commenced, being what are commonly known as "one-way clutches." My improved clutch is designed to afford great strength and reliability with the utmost simplicity of construction, and it is provided with means for disengaging it at will, and thereby freeing the driven part, so that the latter may be revolved in either direction.

The accompanying drawings show my improved clutch as applied to a hoisting-drum.

Figure 1 is a longitudinal mid-section of the drum cut in the plane of the line 1 1 in Fig. 2. Fig. 2 is a transverse section of the same, the plane of the section passing between the drum and the wheel, as denoted by the line 2 2 in Fig. 1. Fig. 3 is a longitudinal mid-section, cut in the plane of the line 3 3 in Fig. 2. Fig. 4 is a fragmentary sectional plan, the internal parts being shown in plan and the drum and wheel in section. Fig. 5 shows the divided friction-ring removed, and Fig. 6 shows the lever removed.

Let A denote a gear-wheel fastened to the shaft B of a hoisting-engine, and C a winding drum, which turns loosely on the shaft. The wheel A is driven by a pinion, D, and turns always in the direction of the arrow a in Fig. 2. In hoisting, the drum C is coupled to this wheel and revolves with it; but when the load is lifted high enough and it is desired to lower it, the clutch is disconnected and the drum is revolved backward by the descending load in the manner commonly practiced in the use of hoisting-machines of this character. The wheel A has an annular overhanging flange, b, the interior of which is turned to a true and smooth surface. Inside of this flange is fitted

a friction-ring, E, the periphery of which is turned true and smooth, and which is divided diametrically into two half-rings, as shown best in Fig. 5. The ends c c of these half-rings abut, but their ends d d' are separated somewhat. A lever, G, is formed with a head, e, a tail, f, and a fulcrum-pin, g, as best shown in Fig. 6. The pin g fits into a cylindrical hole, g', in one of the halves of the ring E, near its end d'. (Best shown in Fig. 5.) When the lever is thus fulcrumed to the ring E, its head e projects into the space between the ends d and d', and the end surface of the head bears against the end d of the half-ring. If now the lever be rocked in the direction of the arrow 6, its head moving in the direction of the arrow 7 will force the end d of the ring away from the end d', and so expand the ring E and cause it to bind tightly against the inner surface of the flange b. The drum C comes against the edge of the flange b and ring E and holds the latter in place, as shown in Fig. 3, while the lever G projects into a cavity in the end of the drum. Two pins, F and H, are fixed to the end of the drum. The pin F comes against the under side of the tail f of the lever G, and the pin H comes against the end of its head e, as best shown in Fig. 2. In hoisting, the wheel A turns in the direction of the arrow a, and it tends to carry the ring E and lever G around with it. This brings the tail of the lever against the pin F, which resists it in the direction of arrow 5. The further movement of the lever tilts it in the direction of arrows 6 and 7, and causes it to expand the ring E in the direction of arrows 8 and 9. This quickly locks the ring E to the wheel A, and the continued pressure of the lever G against the pin F forces the latter and the drum C to rotate with the wheel A. The greater the resistance to the rotation of the drum the tighter is it coupled to the wheel A. The pin H is not brought into use while the clutch is coupled.

The drum C bears a sliding pin or bolt, I, having a tapered or beveled end, i, which comes beneath the head e of the lever G, as best shown in Fig. 1. When the wheel A has

been stopped and it is desired to disengage the clutch, so that the drum may revolve backward, this pin I is to be pressed in, so that its tapered end shall wedge the head of the lever 5 upward or outward, and cause it to bear with less force upon the end d of the ring until it is so far displaced that it exerts no pressure upon the ring, and the latter turns freely. The drum may then be turned in either direction, so long as the pin I is kept pressed in. In turning forward the pin H pushes the lever G and ring E around with the drum, and in turning backward the pin F performs the like function. Whenever the drum turns independently of the wheel A the ring E revolves freely in the flange b.

The pin I may be moved by any suitable mechanism—such, for instance, as that shown—which consists of a sleeve, J, sliding on the 20 shaft B, and having an arm, to which the pin is attached. This sleeve may be moved by a lever, K, Fig. 3, or otherwise. Only a very slight motion is required to either couple or uncouple the parts, so that the clutch acts 25 very quickly as soon as the pin I is drawn back. As the clutch acts only in one direction, the drum may be turned forward by hand when the engine is at rest, and there is no load upon the drum without pressing on 30 the releasing-pin.

I have described my invention as applied to a hoisting-drum; but it may also be used for transmitting motion to a pulley, or from one shaft to another in line therewith, in 35 which case the pins F, H, and I will be attached to a plate fastened to the second shaft. It is also obvious that the part which carries the pins F, H, and I may be the driving part, and transmit motion to the part to which the 40 flange b is fixed.

My clutch may also be applied in place of a

ratchet and pawl, for causing an oscillating part to impart a forward rotation to the driven part, as for drilling and other purposes.

45

I am well aware that friction-clutches which grip only in one direction have been before invented; also that the employment of divided or sectional friction-rings in friction-clutches is not new, and also that levers have been 50 used to expand such rings.

What I claim as new, and desire to secure by Letters Patent, is—

1. The combination of two rotary parts, one of which is adapted to drive the other in one 55 direction through the medium of a friction-clutch, with a clutch consisting of an annular flange on one of said parts, a pin on the other, a divided expansive ring within said flange, and an expanding-lever fulcrumed to said 60 ring on one side of a division therein, bearing against the same on the opposite side of said division, and adapted to be actuated to expand the ring by the pressure of said pin, substantially as set forth.

2. In a friction-clutch, the combination of annular flange b, expansive divided ring E, lever G, fulcrumed to said ring on one side of a division therein, and bearing against it on the opposite side of said division, and pins 70 F and H, acting against said lever, substantially as set forth.

3. In a friction-clutch, the combination of annular flange b, expansive divided ring E, expanding-lever G, fulcrumed to and extending 75 against said ring, clutching-pin F, and releasing-pin I, all arranged and adapted to operate substantially as set forth.

THEODORE SCHEFFLER.
